United States Patent Office

Des. 224,112
Patented July 4, 1972

224,112

COMBINED DATA TERMINAL AND HARD COPY PRINTER

Carl J. Clement, Mountain View, Calif., assignor to
Pholophysics, Inc., Mountain View, Calif.

Filed Jan. 22, 1971, Ser. No. 109,086

Term of patent 14 years

Int. Cl. D14—02

U.S. Cl. D26—5

Fig. 1

Fig. 2

FIG. 1 is a perspective view, taken from the front and slightly below and to the left of center, of a combined data terminal and hard copy printer showing my new design; and

FIG. 2 is a left side elevational view thereof, the right side being a mirror image of the left side and the top, bottom and rear being conventionally plain.

I claim:

The ornamental design for a combined data terminal and hard copy printer, substantially as shown and described.
